TUBE CONNECTION FOR ROCK DRILLS

Filed Nov. 18, 1926

FIG. 1.

INVENTOR.
Fred M. Slater
BY *Herbert Gilzeder*
HIS ATTORNEY

UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

TUBE CONNECTION FOR ROCK DRILLS.

Application filed November 18, 1926. Serial No. 149,127.

This invention relates to rock drills, but more particularly to a tube connection for fluid actuated rock drills of the hammer type in which a pair concentrically arranged fluid 5 conveying tubes are disposed through the percussive element to communicate with their front ends with a hollow drill steel for delivering cleansing liquid thereto.

The objects of the invention are to securely 10 hold a pair of concentrically arranged tubes in the back head of a rock drill in a simplified and improved manner, to simplify the construction and reduce the cost of manufacturing connections of this type, and 15 to render the parts which comprise the connection incapable of being improperly assembled.

Other objects will be in part obvious and in part pointed out hereinafter.

20 The invention consists of the combinations of elements, and arrangement of parts substantially as hereinafter described and claimed and illustrated in the accompanying drawings in which

25 Figure 1 is an elevation, partly in section, of a rock drill equipped with a connection constructed in accordance with the practice of the invention, and

30 Figure 2 is an enlarged detail sectional elevation of the back head and the tube connection.

Referring to the drawings, the invention is shown embodied in a rock drill having a cylinder A which supports at its rearward 35 end a back head B and at its forward end a front cylinder extension C. The front end of the cylinder extension C supports a front head D in which is disposed a chuck F. The rearward portion G of the chuck F is in this instance of smaller diameter than the forward portion and extends into the cylinder extension C to provide a seat for an anvil block H interposed between a hammer 40 piston J and a hollow drill steel K for transmitting the blows of the piston to the drill steel.

Any suitable means may be provided for securing the casing parts of the drill, such as the cylinder A, the back head B, the front 45 cylinder extension C and the front head D, together. In the drawings, bolts L, only a portion of one of which is shown, are provided for this purpose and these bolts may be held in assembled position by suitable

55 lugs or projections O formed on the casing parts.

In accordance with the present invention, the back head B is provided with a recess P having a threaded portion Q and a plain cylindrical portion R. Leading from the bottom of the recess P through the back head B is a hole S through which extends slidably an air tube T. At the rearward end of the air tube T is formed a flared portion U which cooperates with a tapered seat V at the juncture of the hole S and the recess P to form a fluid tight joint for preventing leakage of cleansing liquid, such as water, from the recess into the cylinder A. The tube T is preferably of a length to extend 70 with its front end to a point slightly rearwardly of the drill steel when said drill steel is in its rearwardmost limiting position.

75 Disposed concentrically within the tube T is a water tube W of somewhat smaller diameter than the bore of the tube T having slightly reduced end X which extends into the hollow bore of the drill steel K. The tube W carries a flange Y near its rearward end, thus leaving an end Z projecting rearwardly of the flange which extends slidably into a bore b of a water plug c for holding the said tube W concentrically within the tube T.

80 The water plug c also serves to seal the recess P and is tapered at its forward end d to form a chamber e in the recess P for the reception of water which may be conveyed into the drill through a conduit f leading from a suitable source of supply (not shown). A passage g in the back head B affords communication between the chamber e and the conduit f.

85 A passage h leading from the tapered portion of the plug c to the rearward end of the bore b into which the tube W extends serves to convey the water from the chamber e to the water tube W.

90 In connections of this type, considerable difficulty is at times experienced, due to leakage of water from the back head into the percussive cylinder. The results of such leakage on the movable parts of the rock drill are well known. Various means have heretofore been devised for forming a perfect seal between the water tube connection and the cylinder. Such means, however, are usually of rather complicated construction

and require a multiplicity of parts which increase the cost of construction considerably. The present invention aims to overcome these limitations and to this end a plug *j* is disposed in the front or inner end of the recess *P* and has a tapered portion *k* which fits into the flared end *U* of the tube *T*. The plug *j* is provided with a central aperture *o* through which the water tube *W* extends and this aperture *o* is preferably of such diameter throughout its length that the plug *j* will not contact with the tube *W*. In the present instance, the plug *j* is provided with a transverse passage *p* which affords communication between the aperture *o* and the front or inner end of the recess *P* for conveying pressure fluid to the tube *T*, such pressure fluid being conveyed to the recess *P* through a passage *q* adapted to communicate with any suitable source of pressure fluid supply. A rubber packing *r* is disposed between the flange *Y* of the tube *W* and the plug *j* for preventing leakage of water from the chamber *e* into the inner end of the chamber *P*.

By means of the present invention, leakage of water from the back head into the cylinder will be entirely prevented. This is due largely to the novel manner in which the tubes may be secured in position and also to the simple machining operations which this construction permits. Additional advantages of the present invention are that in the event that excessive force be ap-

plied to the water plug *c* for screwing it into the recess *P*, there will be no likelihood of breakage of any parts to which such force is transmitted, the parts comprising the connection are constructed with a view of preventing improper assembly of the connection, and there are only a few parts required to obtain all the desirable features sought for in devices of this character.

I claim:

In a fluid actuated rock drill, the combination of a cylinder, a back head for the cylinder having a recess, a tapered seat in the bottom of the recess, a pair of concentrically arranged tubes extending through the cylinder and into the recess, a flared portion on the outer tube to cooperate with the tapered seat for forming a fluid tight joint, a flange on the inner tube, a tapered plug seated in the flared end of the outer tube and loosely encircling the inner tube, a packing between the tapered plug and the flange, and a water plug screwed in the recess bearing on the flange to compress the packing and to hold the tapered bore and the flared portion of the outer tube firmly on their seats, said water plug having an aperture to receive the rearward end of the inner tube for holding said inner tube concentrically with respect to the outer tube.

In testimony whereof I have signed this specification.

FRED M. SLATER.
